(57) **CLAIM**

I claim the ornamental design for a bottle top with clip, as shown and described.

DESCRIPTION

FIG. 1 is a perspective view of a bottle top with clip.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

In the drawings, the broken lines depict environmental subject matter only that forms no part of the claim.
